DESIGN FOR A VULCANIZER MACHINE FRAME

Leonard Steiner, Stamford, Conn.

Application August 23, 1945, Serial No. 121,595

Term of patent 14 years

(Cl. D81—1)

To all whom it may concern:

Be it known that I, Leonard Steiner, a citizen of France, residing at Stamford, in the county of Fairfield and State of Connecticut, have invented a new, original, and ornamental Design for a Vulcanizer Machine Frame, of which the following is a specification, reference being had to the accompanying drawing, forming part thereof.

Figure 1 is a perspective view of a vulcanizer machine frame showing my new design; and Figure 2 is an end view thereof.

I claim:

The ornamental design for a vulcanizer machine frame, as shown.

LEONARD STEINER.
